UNITED STATES PATENT OFFICE

2,519,611

FOUNDATION GARMENT

Sally Whitmore Thalman, Bridgeport, Conn., assignor to The Warner Brothers Company, Bridgeport, Conn., a corporation of Connecticut

Application December 26, 1946, Serial No. 718,321

4 Claims. (Cl. 2-37)

1

This invention relates to ladies' foundation garments and is particularly concerned with the provision of a novel and improved type of girdle having important advantages.

An object of the invention is to provide a foundation garment which attains a firm and effective control over the buttocks and thighs of the wearer and which at the same time enables advantageous freedom of movement of the wearer in walking and sitting.

More specifically, the invention provides a foundation garment having at the rear a panel of material capable of stretching up and down but not across the wearer, which panel is narrow at its top and is so wide at its bottom as to extend not only over the lower portion of the buttocks but also around the sides of the thighs and partly to the front of the wearer. The portions of the garment at the sides of said rear panel include material stretchable both up and down and across the wearer, which material extends over at least the major area of the upper rear portion of the garment not occupied by said vertically stretchable rear panel, and also extends over substantial portions of the front of the garment from the region of the waist line to the lower portion of the garment.

Further features and advantages of the invention will be hereinafter described and claimed.

In the accompanying drawings:

Fig. 1 is a front view of a girdle embodying the invention.

Fig. 2 is a rear view of said girdle.

Figs. 3 and 4 are rear and front views, respectively, showing the invention embodied in a panty-girdle.

Referring to Figs. 1 and 2 of the drawings, the girdle there illustrated includes a front panel 1, a pair of intermediate panels 2, 2, and a rear panel 3. The rear panel is of one-way stretch fabric, i. e., material including elastic yarn so arranged that the material is capable of stretching in one direction but is substantially unstretchable at right angles thereto. It is so cut that the stretch of the elastic threads is substantially vertical on the wearer.

As shown, said panel 3 is narrow at its top. It extends downwardly from the top of the girdle, which lies in the region of the wearer's waist line. Said panel also increases in width so that, in the lower portion of the garment, it extends completely around the rear and sides of the garment and partly to the front. Thereby it covers the lower portions of the wearer's buttocks and the sides of the thighs.

2

The front panel 1 of the garment may likewise be of material stretchable up and down but not across, or, if desired, of material substantially inelastic or unstretchable both vertically and horizontally.

The panels 2, 2, interposed between the front panels 1 and 3, are of two-way stretch fabric, i. e., material capable of stretching not only up and down but also across. Each of the intermediate panels 2, as shown, extends from the top to the bottom of the girdle at the front, between the front panel 1 and the front extensions of the panel 3. Each panel 2 also extends around the sides of the garment into the rear portion thereof, between the top of the garment and the edges of the rear panel 3.

The panels 2, 2 are joined at their front edges to the adjacent edges of the panel 3 by stitching 4, 4, which stitching is preferably of zig-zag character to permit the desired stretching along the seams. However, lap joints and other types of stitching might be substituted. Likewise, the panels 2, 2, are joined at their other edges to the edges of the panel 3 by similar stitching 5, 5 of zig-zag or other suitable type.

The two-way stretch material forming the panels 2, 2 is so cut that the transverse stretch of the elastic threads is substantially horizontal on the wearer's figure, and the longitudinal stretch substantially vertical. As has been above noted, the stretch of the elastic threads in the panel 3 is substantially vertical on the wearer. Since that panel is substantially inelastic horizontally of the wearer, and since its lower portion extends around the buttocks and sides of the thighs to the front of the wearer, it exerts a firm control and confining effect on the wearer's body. At the same time the two-way stretch panels 2, 2, extending between the panel 1 and the front edges of the panel 3, provide effectively for desirable freedom of leg movement in walking or sitting. This freedom of movement is further accentuated by cutting of the lower front edges 6, 6 of the panels 2, 2 on the bias, as shown in Fig. 1. Also, the front hose supporters 7, 7 may advantageously extend on the bias, as shown.

It will also be seen that the greatest elasticity is provided in the top portion of the girdle, due to the horizontal stretch of the upper portions of the panels 2, 2 between the panel 1 and the narrow top portion of the panel 3. This increased elasticity in the waist line region enables the garment to contract effectively over small lines and thereby to be readily adaptable to figures

having maximum difference between waist and hip measures.

In Figs. 3 and 4, the invention is shown embodied in a garment of the panty-girdle type. The panels are generally the same as those shown in Figs. 1 and 2, except that they extend into the leg portions 8, 8 of the garment. Also, the rear panel is shown as of more triangular shape than is the rear panel in Figs. 1 and 2. The panels in Figs. 3 and 4 are designated by the same reference numerals as the corresponding panels in Figs. 1 and 2, except for the addition of a prime to each of said numerals in Figs. 3 and 4.

As will be apparent, the girdles in connection with which the invention is illustrated may form portions of other garments, such as the well-known "combinations" in which a girdle and a brassière form part of the same garment. In Figs. 3 and 4, the girdle is shown as having joined thereto at its top a circumferentially elastic band 9 having short vertical stays 10 of suitable stiffening material, as is customary in many girdles.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. A foundation garment comprising a rear panel of one-way stretch material, stretchable in a vertical direction, said panel extending downwardly from the central part of the waist-line portion of said garment, the lower portion of said rear panel extending laterally at opposite sides completely across the side portions of the garment and into the front thereof for covering the wearer's buttocks and the outer sides of the thighs, panels of two-way stretch material joined to adjacent edge portions of said rear panel, said two-way stretch panels extending upwardly and outwardly from said rear panel over substantially the remaining area of the rear of the garment, and continuing around the sides and thence over substantial portions of the front of said garment, and means at the front of said garment for uniting said side panels.

2. A foundation garment comprising a rear panel of one-way stretch material, stretchable in a vertical direction, said panel extending downwardly from the central part of the waist-line portion of said garment, the lower portion of said rear panel extending laterally at opposite sides completely across the side portions of the garment and into the front thereof for covering the wearer's buttocks and the outer sides of the thighs, panels of two-way stretch material joined to adjacent edge portions of said rear panel, said two-way stretch panels extending upwardly and outwardly from said rear panel over substan-

50

tially the remaining area of the rear of the garment, and continuing around the sides and thence over substantial portions of the front of said garment, and a panel at the front of said garment joined adjacent its side edges to the corresponding edge portions of said two-way stretch panels.

3. A foundation garment comprising a rear panel of one-way stretch material, stretchable in a vertical direction, said panel extending downwardly from the central part of the waist-line portion of said garment, the lower portion of said rear panel extending laterally at opposite sides completely across the side portions of the garment and into the front thereof for covering the wearer's buttocks and the outer sides of the thighs, panels of two-way stretch material joined to adjacent edge portions of said rear panel, said two-way stretch panels extending upwardly and outwardly from said rear panel over substantially the remaining area of the rear of the garment, and continuing around the sides and thence over substantial portions of the front of said garment, the lower front edges of said two-way stretch panels being cut on the bias, and a front panel of said garment joined adjacent its side edges to the corresponding edge portions of said two-way stretch panels.

4. A panty-girdle comprising a rear panel of one-way stretch material, stretchable in a vertical direction, said panel extending downwardly from the central part of the waist-line portion of said girdle, the lower portion of said rear panel extending laterally at opposite sides completely across the side portions of the girdle and into the front thereof for covering the outer sides of the thighs of the wearer, panels of two-way stretch material joined to adjacent edge portions of said rear panel, said two-way stretch panels extending upwardly and outwardly from said rear panel over substantially the remainder of the area of the rear of the girdle, and continuing around the sides and thence over substantial areas of the front of said girdle, leg portions in the lower part of said girdle formed completely by portions of said side and rear panels, and a front panel joined to adjacent edge portions of said two-way stretch panels.
